JAMES R. MCWANE, OF BIRMINGHAM, ALABAMA, ASSIGNOR TO MCWANE CAST IRON PIPE COMPANY, OF BIRMINGHAM, ALABAMA, A CORPORATION OF ALABAMA

FLASK SECTION FOR MOLDING CAST-IRON PIPES AND THE LIKE

Application filed March 19, 1928. Serial No. 262,683.

This invention relates to apparatus which is advantageously used for molding long cast iron pipes, although capable of other uses and, among other objects, aims to provide an improved pattern plate and improved flask sections co-operating therewith to expedite making multiple molds. The apparatus is preferably employed in connection with the system described and claimed in my co-pending application, Serial No. 220,731 filed September 20, 1927.

Referring to the accompanying drawings of a preferred form of the invention:—

Fig. 1 is a top plan view of the drag 15 section of a flask;

Fig. 2 is a fragmentary plan view of the drag of Fig. 1;

Fig. 3 is a side elevation, partly in vertical section, of the same;

Fig. 4 is a sectional view taken on the line 4—4 of Fig. 1 and also showing, in dotted outline, a cope arranged on the drag;

Fig. 5 is an elevation of a portion of a 25 jolt rammer with the pattern plate thereon, the patterns being in section, and a flask section shown above the pattern plate in cross section and ready to be rammed;

Fig. 6 is a fragmentary side elevation, on 30 an enlarged scale, of the preferred means for holding the pattern plate and flask sections together;

Fig. 7 is a fragmentary top plan view, also on an enlarged scale, of the holding 35 means of Fig. 6;

Fig. 8 is a perspective view of the wedge forming part of the holding means of Fig. 6;

Fig. 9 is a fragmentary sectional view, on an enlarged scale of a flask section on a 40 pattern plate; and

Fig. 10 is a fragmentary sectional view of one end of the pattern plate showing a guide pin for a flask section.

In the manufacture of cast iron pipe in 45 horizontal molds, by what is known as the green sand process, the practice heretofore has been to use a molding machine having a stripping plate and drop pattern. One section of the flask is rammed at a time, and the rammed sections are removed and

matched together with the core bar or bars between them.

There are some objections to the use of these stripping plates and drop patterns, the principal objection being that, in the course of time, the patterns and stripping plates both wear and it is then quite difficult to keep them properly adjusted. Moreover, in ramming pipe flasks on a jolt rammer, the mechanism of the drop pattern will not withstand rough usage. Therefore, when employing the system heretofore in use, it has been necessary to ram the flasks by hand, which is laborious, expensive and slow.

To speed up production and to economize in the manufacture of cast iron pipes and the like, it is highly desirable to employ the jolt ramming machines. To use this ramming apparatus successfully, it is necessary to employ "pattern plates" or "match plates". Such pattern plates have one-half of the patterns fastened to them and are made so as to permit lifting the flask sections off them after the jolt ramming. In the process of molding, each pattern plate in one operation forms one half of one or more pipe molds and these halves (the flask sections) are subsequently matched together, with the cores properly placed in the molding space to make the complete mold.

In using a pattern plate, it is very difficult to prevent what is called "ratting", this being a sticking of the sand along the edges of the pattern, which results in an imperfect mold. It will be readily understood that this is much more easily prevented when the pattern is dropped through the stripping plate away from the mold, as in the old process, than it is when the flask section, with the molds formed therein, is lifted from a stationary pattern attached to the pattern plate. The present invention provides a pattern plate so made as to give a "perfect lift", that is, a clean separation of the mold from the pattern plate, without injury to the mold.

In the manufacture of long cast iron pipe, it is further necessary to obviate deflections of the rammed flask sections when they are

lifted free of the pattern plate such as will injure or destroy the molds. Moreover, long flask sections are subjected to lateral displacement relative to the pattern plates and this also results in destruction of or serious injury to the molds. Hence, it is highly desirable positively to hold the flask sections between their ends to the pattern plate, and by holding means such as are capable of being used when the flask sections become warped or permanently deformed.

To summarize the improvements effected by the invention: first, the long flask sections are made as rigid as possible to obviate deflection such as will be destructive to the molds; second, the means for holding the flask sections on the pattern plate are made capable of preventing any relative lateral movement while the flask section is being rammed by the jolt rammer; and third, the patterns on the pattern plate are constructed so that all of them have the proper draft at and near the point where they contact with the pattern plate, whereby the flask sections can be lifted without damaging any mold.

Referring specifically to the drawings, there is shown in Fig. 1, a drag section of a multiple pipe flask designed to be employed in conjunction with a pattern plate, the drag shown also typifying the construction of the cope, which is not shown except in dotted lines, Fig. 4. Herein, the drag section is shown as having provision for molding four long sections of pipe at one time although it is to be distinctly understood that any convenient number of pipe sections may be made, within the mechanical limits of the apparatus. The drag shown is generally rectangular in outline and has a single pair of axially aligned trunnions 20 arranged on its longitudinal axis and projecting from the end walls 21 so that the drag may be picked up by an overhead crane or carrier and conveyed about the plant.

To distribute the weight and the load of the rammed flask sections and to strengthen them so as to avoid undue deflection when picked up by the crane, which would destroy the rammed molds, a plurality of reinforcing members are shown extending both longitudinally and transversely of the illustrative drag. Herein, a longitudinal web 22 (Figs. 1 and 5) extends from end to end of the drag along a medial plane, and intermediate the ends of the drag, the web 22 is shown as being divided, forming a pair of spaced branches 23 affording greater strength or bending resistance where the greatest deflection would otherwise occur. The web 22 is enlarged adjacent to the points where the bell ends of the molds are formed and the branches 23 begin adjacent

to the bell, as indicated in dotted lines, Fig. 1.

Referring to Fig. 4, the branches 23 of the web are shown as separating the flask section into two pouring units and provision is made to permit gases from the molds, during or after the pouring operation, to escape between the branches. The branches are shown as being connected along the inner edges by a horizontal strengthening web 24 (Fig. 4) and this web has a plurality of perforations 26 through which the gases may escape.

Within the interior of the drag are shown a plurality of spaced, transverse strengthening webs 27 which are integral with the side walls 28 and with the longitudinal web 22 and its branches 23. These transverse webs present clearance openings for the cores which are placed in the flask sections. Certain of the transverse webs 27 are shown (Fig. 2) as, in effect, extending across the space between the branches 23 of the web 22. In other words, the branches 23 are connected at regular intervals by transverse webs which are aligned with some of the transverse webs 27 to make the flask section more rigid and thus prevent destructive lateral deflections.

The drag section is shown as having integral brackets 29 (Figs. 1 and 3) and bolt receiving notches 30 at each end for adjusting the core bars, as disclosed in my Patent No. 1,601,450, dated September 28, 1926. Further at the bell end of the flask section there are shown a plurality of machined bosses 31 to guide the core bars longitudinally when they are lowered into the drag, as disclosed in my divisional application, Serial No. 343,887, filed March 2, 1929.

As will be understood, the cope section of the flask is similar in most respects to the drag section. It is not necessary, however, to provide the brackets 29, the bolt notches 30 and the machined bosses 31 for the core bars on the cope section. A detailed description of a cope section will therefore be omitted.

Referring now to Fig. 5, the drag section is shown applied to a pattern plate 32 on the surface of which is secured a plurality of half pipe patterns 33. The pattern plate is preferably approximately the same width as the flask section. To guide the flask section on the pattern plate and to prevent relative longitudinal displacement, tapered guide pins 34 (Fig. 10) are provided at diagonally opposite corners of the pattern plate and co-operate with bushed holes or openings 35 in the flask section (Fig. 1). One of the holes is shown as being substantially elliptical so that it will receive its pin notwithstanding slight variations in length of the flask section, due to expansion or contraction.

To hold the flask section intermediately to the pattern plate, a pair of opposed brackets 36 (Figs. 5, 6 and 7) are shown as being bolted to the sides of the pattern plate and have overhanging portions for receiving holding wedges 37 between opposed, compound tapered faces thereon and co-acting bosses or pads 38 on the flask section having machined vertical faces. The taper of the 5 wedges is both longitudinal and transverse (Fig. 8) so that when the wedges are inserted between the wedge receiving faces, their thickest portions at the bottom rest against a suitable shoulder 39 on the brackets 10 whereby they tighten themselves automatically when the jolt rammer 40 is reciprocated up and down. The described wedge means will engage and hold slightly warped flask sections. Moreover, the arrangement is such that the plane faces of 15 the wedges which engage the bosses or pads 38 are also vertical and act as lateral guides for the flasks when they are being lifted from the pattern plate, thus preventing 20 ratting.

After the flask section is thus located on the pattern plate, it is supplied with green sand and the jolt rammer 40 is operated. The section is jolted until the sand is well 25 rammed; then the ramming operation is completed by manually operated pneumatic rammers. To permit the flask sections to be removed from the pattern plate without destroying any part of the mold or without 30 "ratting", the patterns 33 (Figs. 5 and 9) are shown as being flattened or cut away adjacent to their junctions with the surface of the pattern plate. If the patterns were not cut away there would be portions of 35 their surfaces adjacent to their junctions with the pattern plate which would be substantially vertical. Hence, there would not be sufficient draft for the patterns to permit the flask sections to be removed without 40 destroying the molds. Herein, the patterns have planed surfaces 41 extending upwardly at an angle of a few degrees from their junctions with the pattern plate to afford ample draft. I have found by many hundreds of 45 trials that it is only necessary to cut away a few thousandths of an inch of the thickness of the pattern, to provide this draft. Figs. 5 and 9 greatly exaggerate the flattened surfaces of the patterns so as to make 50 them apparent.

I have also found that the sand adjacent to the surface of the pattern plate and around the edges of the patterns is not and 55 cannot be rammed as tightly as the sand in other portions of the molds. Consequently, when the metal is poured, its weight will compress the somewhat looser sand where the flat surfaces appear and thus increase 60 the thickness of the castings so that each is

of substantially uniform thickness, with no perceptible flattening anywhere.

From the foregoing description, it will be seen that the improved apparatus here provided permits rapid preparation of pipe 70 molds and the like practically entirely by mechanical means. There are no parts of the patterns or flask sections which can be distorted during the ramming operation. Further, ratting and consequent destruction 75 of the molds is practically eliminated by the form of the patterns. Also, the flask sections are so constructed as to obviate deflections destructive to the molds when they are being handled by a crane. The apparatus 80 makes practically perfect molds and will therefore permit the manufacture of long sections of pipes having thinner walls than could be produced by old methods.

The pattern plate, the wedges and certain 85 co-operating parts are claimed in a divisional application Serial No. 436,751 filed March 18, 1930.

Obviously, the present invention is not restricted to the particular embodiment 90 hereof herein shown and described. Moreover, it is not indispensable that all the features of the invention be used conjointly, since they may be employed advantageously 95 in various combinations and sub-combinations.

What is claimed is:—

1. A flask section for the molding of a plurality of cast iron pipes horizontally, having provision at its opposite ends to 100 be lifted horizontally and double longitudinal strengthening webs separating the flask section into pouring units and arranged to prevent destructive deflections of the flask when rammed and lifted.

2. A flask section for the molding of a plurality of cast iron pipes horizontally, having double longitudinal strengthening webs separating the flask section into pouring units, said double webs extending 110 through the center portion of the flask section and merging into single webs at each end thereof; and means at the opposite ends of the flask section opposite said single web whereby it may be lifted horizontally.

3. A flask section for the molding of a plurality of cast iron pipes horizontally, having double longitudinal strengthening webs separating the flask section into pouring units, said webs being joined at their inside edge by an integral web; and lifting trunnions on the ends of said section alined with said webs.

4. A flask section for the molding of a plurality of cast iron pipes horizontally, 125 having double longitudinal strengthening webs separating the flask section into pouring units, said webs being joined at their inside edge by an integral web, and the integral web being depressed at intervals be- 130

low the parting plane and perforated to allow the flow and escape of accumulating gases.

5. A metal flask section for molding a plurality of elongated castings horizontally comprising, in combination, a body having end and side walls; and a strengthening web extending longitudinally of the body and integral with the end walls; said web having a pair of integral branches extending parallel to each other for the greater part of the length of the flask section and being relatively close together; the two spaced branches being sufficiently massive to strengthen the flask section in the central part and thus obviate such deflection in the central part as will be destructive of the mold; the space between the branches of the longitudinal web permitting the provision of perforations for the escape of gases formed during casting and freezing of the metal.

6. A flask section for molding a plurality of elongated castings horizontally, having a pair of spaced longitudinal webs dividing the section into pouring units; and a plurality of transverse webs connected to the longitudinal webs, some of the transverse webs extending across the space between the longitudinal webs.

7. A flask section for molding a plurality of long cast iron pipes comprising, in combination, axially aligned trunnions at the opposite ends; and a strengthening web extending longitudinally of the flask section between said trunnions to obviate destructive sagging of the rammed flask section when it is lifted by said trunnions.

8. A flask section for molding a plurality of long cast iron pipes comprising, in combination, a pair of trunnions at the ends on the longitudinal axis of the flask section; and longitudinal and transverse strengthening webs integral with the walls of the flask section arranged to obviate destructive deflection when the rammed flask section is lifted or transferred from a pattern.

9. A flask section for molding a plurality of long cast iron pipes comprising, in combination, a pair of trunnions on the opposite ends on the longitudinal axis of the flask section and a strengthening member inside the flask section between the trunnioned ends to resist sagging of the flask in the middle after it is rammed and lifted from a pattern.

10. A flask section for molding a plurality of long cast iron pipes comprising, in combination, a pair of trunnions at the ends on the longitudinal axis of the flask section; and longitudinal and transverse strengthening webs integral with the walls of the flask section arranged to obviate destructive deflection when the rammed flask section is lifted or transferred from a pattern; said

strengthening member including a pair of spaced longitudinal webs dividing the flask section into two pouring units.

In testimony, that I claim the foregoing as my own, I have hereto affixed my signature.

JAMES R. McWANE.
